UNITED STATES PATENT OFFICE.

CLIFFORD M. WATROUS, OF EAST HAMPTON, CONNECTICUT, ASSIGNOR TO GONG BELL MANUFACTURING COMPANY, A CORPORATION OF CONNECTICUT.

TOY TELEPHONE TRANSMITTER.

Application filed May 13, 1925. Serial No. 29,852.

To all whom it may concern:

Be it known that I, CLIFFORD M. WATROUS, a citizen of the United States, and a resident of East Hampton, in the county of Middlesex and State of Connecticut, have invented certain new and useful Improvements in Toy Telephone Transmitters, of which the following is a description.

This invention relates to toy telephones and is particularly related to the transmitter employed in an assembled device in conjunction with a base, standard, transmitter and receiver with appurtenant parts, all in simulation of a standard type of telephone.

Usually, these toy devices have some signalling or sound producing mechanism which can be operated by the child in play, to approach in operation, the effects of a telephone.

In a co-pending application, Serial No. 566,903, filed June 8, 1922, I disclosed and claimed a telephone transmitter having certain features of advantage and the present invention is directed to special features of such a transmitter which in manufacture, have been found to improve the art of production and provide a more substantial element.

In toy manufacture, it is essential to secure appearance of the highest character, in conjunction with stability, as toys ordinarily receive rather rough usage.

It is in the elements of advantage to the article and advancement in the art of manufacture, that the essence of the present invention resides.

For purposes of illustration, the transmitter is illustrated, in conjunction with a desk set, in simulation of a standard type of telephone.

The main object of the invention is to produce a transmitter, component parts of which may be readily fashioned, assembled and secured in interlocked arrangement and without liability of buckling of the parts through lack of skill of the operative during assembly.

Referring to the drawings:

Figure 1 illustrates a telephone set of the toy type.

Figure 2 is a sectional view through the transmitter, and its supporting element.

Figure 3 illustrates the parts in position for assembly.

Figure 4 is a section through a modified construction in which certain of the parts are spun together.

Figure 5 shows an elevation of the supporting bar employed in Figure 4.

Figure 6 is an end view of the same. 60

Figure 7 illustrates a modified form of supporting bar.

Figure 8 shows a two piece bar.

Figure 9 illustrates the parts assembled.

Figure 10 is a side elevation of a modified form of bar. 65

Figure 11 is a sectional view.

Figure 12 illustrates a non-slipping closure plate.

In the manufacture of toys of the type 70 herein described, the essentials are economy in "stock", simplicity in formation and assembly of the parts and "sturdiness" of the completed article. At first sight, these requirements would seem to be easy of accomplishment, but it has been found, in actual manufacture, that what are apparently slight details, become all important factors in actual manufacture of high grade goods meeting the above qualifications. 80

Utilizing the invention as expressed herein, comparatively light "stock" may be employed which when submitted to the action of dies or spinning operations, gives a uniform product which permits of high "production." This "stock" is so utilized with various elements that assembly may be effected even with unskilled labor. Provision is made through the elemental functioning of the parts to obviate liability of imperfect 90 goods which would ordinarily occur in assembly unless the assembly were made by skilled labor and with great care. In fact, the elements must be reduced to a form in which they may be stamped out and spun up, spun together, interlocked and clamped, one with reference to the other, without requiring trimming, fitting and particular care in the assembly. 95

Referring to Figure 2, there is illustrated 100

a transmitter having the general elements of those heretofore described in my prior application.

There is a supporting bar 1, which, as 5 illustrated, is stamped out in a form to afford an abutment 2, against which the shell 3, of the transmitter may rest.

There is a closure for this transmitter, 10 which as illustrated, is in the form of a disk 4, and there is a mouthpiece 5.

It is essential that these various parts be bound together to form a stable structure and to effect this, the bar 1, extends through the plate 4, and mouthpiece 5, these parts 15 having suitable slots or openings for the purpose. The end of the bar is then swedged down so that the shell 3, and closure, consisting of the disk 4, and its mouthpiece 5, are firmly interlocked against the 20 abutment 2, of the supporting bar 1.

In my prior application, no particular provision was made for preventing buckling of the parts when the swedging tool deformed the metal at the end of the bar 1, 25 and this resulted in some loss during production.

Over zealous operatives would often depress the swedging tool to such an extent as to either buckle the closure plate, mouthpiece or the shell.

Even where assembly was effected in a proper manner, there was still objection inasmuch as the closure plate 4, was liable to shift with reference to the base 3. This 35 occurred at times during assembly and even after assembly, if a toy were dropped so that the disk 4, was given a sharp blow it was liable to distort the assembled parts.

In order to prevent slippage of the closure plate 4, such an arrangement as illustrated in Figure 12, is desirable and this may be used with, or without the stop block hereinafter specified. When used with the stop block, there is assurance that there will 45 be no buckling of the parts during the swedging operations. When used without the stop block, there is no opportunity of slippage between the base and the closure plate, inasmuch as the latter is centered by 50 its annular rim hereinafter described.

To overcome these objections, I now employ a stop block 6. This may be of cylindrical form and is slipped over the outer end of the bar 1, after the shell 3, has been 55 assembled thereon. The closure, consisting of the plate 4, and mouthpiece 5, are also slipped over the end of the bar 1, and rest upon one end of the stop block 6.

It follows that there is a substantial 60 abutment surrounding the bar 1, and against which the upsetting tool for the end of the supporting bar 1, may impinge to a considerable extent without liability of buckling any of the parts.

65 This arrangement has unusual advantages

as it speeds up manufacture, assures perfect goods and adds comparatively no expense. The stop blocks may be formed of any inexpensive material such as a wood block.

70

This stop block is particularly advantageous in conjunction with the various forms of transmitters illustrated. In Figure 4, the shell of the transmitter is composed of two parts, 7 and 8, which are stamped and 75 spun up. The base part 7, of the shell, has a lip 9, of sufficient length to be spun over a flange 10, of the co-operating part 8.

In assembling, the bar 1, has the lower section 7, stop block 11, co-operating section 8, and mouthpiece 13 arranged thereon and the deforming tool then upsets the end 14, of the bar to secure the elements in fixed position on the bar 1. The edges of the two parts of the shell are spun one over the 85 other giving an extremely firm construction and one of very attractive appearance.

Very light metal may be employed in this form of device as the annular ring or rim, formed by spinning the parts together, surrounds the transmitter and acts as a stiffener to prevent displacement, buckling or denting of the thin metal.

Very light metal may be employed in this form of device as the annular ring or rim, formed by spinning the parts together, surrounds the transmitter and acts as a stiffener to prevent displacement, buckling or denting of the thin metal.

The supporting bars for the transmitters may be of any desired form. In Figures 1 to 4, they are shown as stamped from sheet stock and they may be perforated for a pivot to be attached to the standard or may be stamped out of an angular piece, all to suit the exigencies of any particular requirement.

In Figure 7, there is illustrated a bar which has all the necessary features for an abutment against which to bind the parts of the transmitter. In this figure, a blank is formed from thin sheet and folded upon itself as on the dotted line, causing its two parts to be superposed so that a cutout portion of the blank will provide a shoulder 12, at the proper distance from the end of the bar 15. The end of the bar 16, may be suitably formed so that it may be swedged down after the shell parts, mouthpiece, etc., are in place thereon.

If it is desired to form a distinct shoulder for an abutment at opposite sides of the bar, which of course, is preferable, the die will strike out or deform the metal as at 14^a, so that the end of the folded section as at 12, will form a shoulder on one side and the deformed part of the body of the blank in line therewith, will be offset at the opposite side.

In Figures 8 and 9, this same result may be attained by striking out a long body part 17, and a shorter body part 18, and then superposing the two parts, spot welding the thin metal to form a plate bar, as shown in Fig. 9, which will have abutments 19, 20, against which the shell may be bound.

130

In lieu of the form shown in Figures 7 to 9, lugs may be upset in the body of the bar 21, as at 22, 23, one being thrown to one side of the bar while the other is thrown to the opposite side thereof. This obviously will give an abutment against which the swedging operation may occur for binding the parts together. These various forms of supporting bar described may be used with facility in conjunction with the stop block which acts as a "take up" and spacer between the elements to be assembled when the swedging tool deforms the end of the bar to permanently lock the parts together.

In Figures 5 and 6, in place of using the conventional flat stock, "rod" stock of appropriate size may be employed in which case the outer end, provided it is to be pivoted, may be deformed as at 24, and pierced as at 25. The metal is then slabbed from opposite sides as at 26, 27, to provide the abutments 28, 29, and a somewhat reduced end. This end of the bar is then deformed and forced back against the mouthpiece underlying stock plug and abutments 28, 29, thus firmly securing the parts both against longitudinal movements, relative rotation, and lateral movement.

In Figure 12, there is the same elemental arrangement as in the above described devices.

The form of the closure plate 50, however, instead of being a flat plate, as heretofore illustrated, has a depression 51, concentric with its periphery and so formed that the depressed metal forms an annular like ring 52, which surrounds the outer edge 53, of the base part 3.

This annular ring 52, centers the closure plate 50, on the base and materially stiffens the plate so that it may be secured in place without difficulty by swedging the end of the supporting bar 1.

There is no objection to using this deformed plate, in so far as appearance is concerned, as in all of the structures, there is the celluloid or similar disk A, which covers the plate and carries the trade name and other suitable indicia and this, of course, covers the groove 51, giving a neat appearance to the device.

It will be obvious, from the above, that while an abutment on the bar acts as a stop for the shell of the transmitter casing, such an abutment, in conjunction with a stop block, opens a wider field for manufacture, as any of the forms of bars hereinabove described may be used successfully with such a stop block.

There is no difficulty in making the parts of the shell with exactitude, as of course, these are struck up on dies or spun up as the case may be, with exactitude. When they are assembled, as hereinabove described, in conjunction with the stop block, there is

practically no loss due to improper assembly and careless use of swedging tools in locking the parts together upon the bar.

What I claim as my invention and desire to secure by Letters Patent is:

1. As an article of manufacture for a toy telephone, a transmitter having a supporting bar, a transmitter shell, a closure for the transmitter shell, and a mouthpiece mounted on said bar and means appurtenant to the peripheral edge of the closure and the edge of the shell for preventing relative lateral displacement of said parts and means upon the supporting bar for binding the various transmitter parts in fixed position thereon.

2. As an article of manufacture for a toy telephone transmitter having a supporting bar, a transmitter shell, a closure for the transmitter shell and a mouthpiece mounted thereon, an annular bead adjacent to the peripheral edge of the closure and co-operating with the edge of the shell to prevent relative lateral displacement of said parts and means upon the supporting bar for binding the various transmitter parts in definite position thereon.

3. As an article of manufacture for a toy telephone, a transmitter having a supporting bar for a mouthpiece, a transmitter shell supported on the bar with said mouthpiece and a stop block within the transmitter shell and surrounding the bar.

4. As an article of manufacture for a toy telephone a transmitter comprising a supporting bar having a shoulder, a transmitter part resting against the shoulder, a closure for the transmitter part and a mouthpiece, a stop block intermediate the transmitter part and closure and a part deformed from the supporting bar within the mouthpiece, said deformation adapted to secure the transmitter parts in place upon the supporting bar.

5. As an article of manufacture for a toy telephone a transmitter comprising a supporting bar for a mouthpiece, a transmitter shell supported thereon, a mouthpiece also supported on the bar, a stop block intermediate the transmitter shell and mouthpiece and means appurtenant to the end of the supporting bar including a deformed end thereof for clamping the transmitter parts and mouthpiece in place upon the bar and against the stop block.

6. As an article of manufacture for a toy telephone, a transmitter comprising a supporting bar, a transmitter shell engaged therewith, a closure for the transmitter shell, and a mouthpiece, a stop block intermediate the transmitter part and mouthpiece and means integral with the support for clamping the transmitter part in place thereon.

7. An article of manufacture in a toy telephone, a transmitter comprising a support for the mouthpiece, a stop for localiz-

ing the mouthpiece and appurtenant parts upon the support, a stop block for spacing the parts arranged within the transmitter, a transmitter part and closure therefor, including a mouthpiece and means deformable from the supporting element for clamping the transmitter parts and mouthpiece to the support and against the stop block.

8. As an article of manufacture for a toy telephone, a transmitter having a supporting bar for a mouthpiece, a transmitter shell supported on the bar with said mouthpiece and a stop block forming an abutment between the parts located within the transmitter shell.

9. As an article of manufacture for a toy telephone, a hollow transmitter casing having a supporting member, said transmitter casing supported and secured thereon, the transmitter casing comprising two cup like parts, each having a flange, the flange of one part spun over the adjacent flange of the other part to provide an annular stiffening band at the medial line of the transmitter casing and a mouthpiece secured on the support appurtenant to the shell.

10. As an article of manufacture for a toy telephone, a transmitter having a supporting member, a transmitter shell supported and secured thereto, said shell comprising two parts spun together at their peripheral edges, a mouthpiece and a stop block arranged within the transmitter shell.

11. As an article of manufacture for a

toy telephone, a transmitter casing and mouthpiece, a bar for supporting said parts consisting of a blanked out sheet and a superposed part formed to provide an abutment against which the transmitter parts rest and may be clamped, the sheet being pressed out to form an offset shoulder opposite the said abutment, the outer end of said bar being formed to clamp the transmitter parts and mouthpiece against the abutment and shoulder.

12. As an article of manufacture for a toy telephone, a transmitter casing and mouthpiece, a bar for supporting said parts comprising a formed up piece providing an abutment against which the transmitter parts rest, the end of said bar being capable of deformation to clamp the transmitter parts, and mouthpiece against the abutment, and a stop block within the shell forming an abutment for the deformation of the end of the bar.

13. As an article of manufacture for a toy telephone, a supporting bar for a transmitter comprising a bar formed from overlaid elements, one of less length than the other, to provide an abutment, a transmitter casing supported thereon, the end of the bar projecting therethrough, and formed to permit deformation at the end to clamp the transmitter parts in place against the abutment.

CLIFFORD M. WATROUS.
